JOSEPH A. S. TAYLOR AND JAMES TAYLOR, JR., OF PHILADELPHIA, PENNSYLVANIA.

LOCKING-HOOK.

No. 909,037.

Specification of Letters Patent.

Patented Jan. 5, 1909.

Application filed March 31, 1908. Serial No. 424,407.

To all whom it may concern:

Be it known that we, JOSEPH A. S. TAYLOR and JAMES TAYLOR, Jr., citizens of the United States, residing at Philadelphia, in 5 the county of Philadelphia and State of Pennsylvania, have invented a certain new and useful Improvement in Locking-Hooks, of which the following is a specification.

Our invention relates to a new and useful 10 improvement in locking hooks, and has for its object to provide an exceedingly simple, effective and satisfactory lever fastener for the side chains of grips or treads for pneumatic tires that will draw them tight and 15 hold them taut.

With these ends in view, this invention 20 consists in the details of construction and combination of elements hereinafter set forth and then specifically designated by the claim.

In order that those skilled in the art to 25 which this invention appertains may understand how to make and use the same, we will describe its construction in detail, referring 30 by letter to the accompanying drawing forming a part of this specification, in which—

Figure 1 is a side elevation of the hook in an open position showing a compression 35 spring and a portion of the chains secured thereto. Fig. 2, a similar view taken at right angles to Fig. 1, and Fig. 3, a view similar to Fig. 1 showing the hook in its closed position.

In carrying out our invention as here 40 embodied, A represents the body of the hook, which has a number of notches B therein; here shown as two in number, for engagement with a link of the side chain C of a pneumatic tire grip, and D represents the combined lever and latch, and is pivoted to the body at E. This latch is provided with the lugs F, to which the member G of the compression spring H is pivoted. 45 the opposite member of the compression spring being attached to the opposite end of the side chain C. The latch D is cut away at I and I' so that in closing, these cut away portions will prevent the latch 50 from interfering with the link of the chain which is in engagement with one of the notches B. An indentation J is formed in

the body with which a detent K pressed into the latch is adapted to engage for holding the latter in its closed position, and thus 55 preventing the link in engagement with the notches B from becoming displaced.

In the use of grip chains for automobiles, great difficulty and annoyance has heretofore been experienced in tightening up the 60 side chains, it requiring a special tool for that purpose which had to be applied to draw up the chain beyond its intended position so as to enable the operator to engage a new link with the hook, and then when 65 the tool was removed the chain naturally fell back and would often be slack, whereas, by the use of our improvement this disadvantage is entirely overcome, the hook being utilized as a lever, it being only necessary to swing the latch backward to the position shown in Fig. 1, take up all the slack 70 possible by the pull of the hand, engaging the proper link with one of the notches B and thereafter by closing the latch the opposite end of the chain will be drawn forward and sufficiently taut to hold it in place. 75 The compression spring H when used in connection with our improved hook serves the purpose of keeping an even tension upon 80 the grip chains.

It is to be understood that the end link may be engaged with either one or the other of the notches B, and when the chain is too long for this link to be utilized the next succeeding link may be used in the same manner.

It is to be noted that by the proper arrangement of the pivots E and F to each other that when the latch is closed the draft 90 of the compression spring thereon will be such as to assist in maintaining said latch in its closed position on account of the point of draft passing below the pivot point E.

Having thus fully described our invention what we claim as new and useful, is—

A locking hook composed of a notched body, a latch pivoted to one end of said body, an outwardly projecting lug on each side of said latch, a chain having one end in 100 engagement with one of the notches of said body, a compression spring secured to the other end of said chain, a member G, having an intermediate bent part, engaging said

2
compression spring and arms which extend on opposite sides of said latch and have their ends bent to form eyes which engage said lugs of the latch, said latch being formed with cut-away parts and having a detent to be received in an indentation in said body provided therefor.

In testimony whereof, we have hereunto

affixed our signatures in the presence of two subscribing witnesses.

JOSEPH A. S. TAYLOR.
JAMES TAYLOR, JR.
